CLAIM

(51) **LOC (9) Cl.** 13-03

We claim the ornamental design for the housing for a modular storage system, as shown and described.

(52) **U.S. Cl.** **D13/162.1**

DESCRIPTION

(58) **Field of Classification Search** D13/101,

FIG. 1 is a perspective view of a housing for a modular storage system showing our new design;

D13/103, 112, 114, 118, 107, 110, 123, 124,

FIG. 2 is a front view thereof;

D13/158-184, 199; 429/12; D23/351, 352,

FIG. 3 is a back view thereof;

D23/317, 318, 319, 320, 329, 332, 330

FIG. 4 is a side view thereof;

See application file for complete search history.

FIG. 5 is a side view thereof showing the side opposite that shown in FIG. 4;

(56) **References Cited**

FIG. 6 is a top view thereof; and,

U.S. PATENT DOCUMENTS

FIG. 7 is a bottom view thereof.
